UNITED STATES PATENT OFFICE.

SIDNEY A. KELLER, OF NEW YORK, N. Y., ASSIGNOR TO MARCUS T. GOLD-SMITH, OF NEW YORK, N. Y.

DESIGN FOR A BAG-FRAME.

SPECIFICATION forming part of Design No. 36,038, dated September 2, 1902.

Application filed September 21, 1901. Serial No. 76,078. Term of patent 3½ years.

To all whom it may concern.

Be it known that I, SIDNEY A. KELLER, a citizen of the United States, and a resident of New York, in the county of New York and State of New York, have invented a new, original, and ornamental Design for Bag-Frames, of which the following is a specification.

In the accompanying drawing, to which reference is made and which forms a part of this specification, the figure illustrates a frame for bags, purses, and similar articles in accordance with my design.

The leading feature of my design consists of a curve at the lower edge, a short central curve at the upper edge, and four scallops each side of the said short central curve, the two lowermost scallops at each side being in the same vertical plane above a straight vertical edge, and of the ornamentation on the surface, as shown and described.

In the drawing, 2 designates the lower curved edge, 3 the opposite short central curve, and 4 5 6 7 the scallops each side of the central curve 3. The scallops 7 at each side is beneath the scallop 6, and each of said 25 scallops 7 terminates in a line 8. The space between the curve 2 and the scallops 3, 4, 5, 6, and 7 is ornamented with volutes and foliation, which form a smooth open shield-like field 9 beneath the short central curve 3, a 30 flower beneath each of the scallops 4, a bud and foliation beneath the other scallops.

What I claim is—

The ornamental design for a bag or purse frame, or similar article, as shown and described.

SIDNEY A. KELLER.
